NUTHOOK

Gordon T. Brummel, Chicago, Ill.

Application March 10, 1951, Serial No. 14,456

Term of patent 14 years

(Cl. D54—11)

To all whom it may concern:

Be it known that I, Gordon T. Brummel, a citizen of the United States, residing at Chicago, in the county of Cook, and State of Illinois, have invented a new, original, and ornamental Design for a Nuthook, of which the following is a specification, reference being had to the accompanying drawing, forming a part hereof.

In the drawing:

Fig. 1 is a side elevational view of a nuthook, showing my new design;

Fig. 2 is a front elevational view;

Fig. 3 is a top plan view;

Fig. 4 is a rear elevational view; and

Fig. 5 is a sectional view, taken on the line 5—5 of Fig. 1.

I claim:

The ornamental design for a nuthook, substantially as shown.

GORDON T. BRUMMEL.
